UNITED STATES PATENT OFFICE.

DONALD McDONALD, OF LOUISVILLE, KENTUCKY.

GAME COUNTER.

Application filed June 12, 1922. Serial No. 567,859.

To all whom it may concern:

Be it known that I, DONALD McDONALD, a citizen of the United States, and a resident of the city of Louisville, in the county of Jefferson and State of Kentucky, have invented certain new and useful Improvements in Game Counters, of which the following is a specification.

My invention relates to game counters and particularly to a tallying system for the game of bridge. As the description of the invention proceeds, however, it will be noted that this counting system is equally adaptable with slight modifications for tallying the scores of other games.

This invention relates mainly to an improvement in the game counter described and claimed in my application Serial Number 468,262 filed May 10th, 1921.

The principal advantage and object of this invention is to provide a simple and convenient device wherein the tallying of the score of the game of bridge is facilitated and whereby the status of each player as regards total score and points in the current game will be always apparent.

By the use of my improved game counter the necessity for keeping any part of the score with pencil and paper is eliminated and the winnings or the losses of each player is constantly apparent. Furthermore, it is highly desirable particularly in scoring the game of bridge to be able to ascertain at any time the status of any player as regards the number of points scored in the current game inasmuch as this oftentimes influences the bidding.

My invention therefore contemplates the provision of means whereby the status of any player as regards total score will be always apparent and also means whereby the total number of points scored by each player on the current game will be apparent as will also the particular game of the rubber in which the points are being scored.

In carrying out my improved system of tallying, I provide a plurality of racks from which project posts adapted to contain chips of distinguishing colors and different valuations. The valuations of the chips are so selected that the majority of scores made at bridge can be paid with a single chip and furthermore that any possible score can be paid by a combination of these chips. To

facilitate the reading of the losses or gains of any player the posts of each rack have delineated thereon in a vertical row the consecutive combined value of the chips both plus and minus and these valuations in distinguishing colors such as for instance, black and red. When therefore, each post has the original number of chips thereon the number zero is visible immediately above the pile of chips while the addition or subtraction of the chips from any post will cover or uncover numbers corresponding to the chip valuation so that always the number visible at the top of the pile of chips indicates the plus or minus value of the chips contained on that post.

For tallying the points of each game and for ascertaining which game of the rubber is being played, there is provided a disc having a double dial-like face upon which is delineated values running from zero to 30. A movable pointer is provided whereby the points of a game may be indicated and the central portion of the disc is differently colored on opposite sides so that when the disc is laid upon the table with one side up it will be understood that the points indicated have been made in the first game, while when the other side of the disc is disposed upwardly it will be understood that the number of points indicated have been made on the second game of the rubber.

The novel combination, construction and arrangement of parts will be made more apparent hereinafter in the accompanying specification and drawings.

In the drawings:

Fig. 1 is a perspective view of one of the racks employed in my improved system of game counting,

Fig. 2 is an enlarged longitudinal section partly in elevation,

Fig. 3 is one face view of the game counting disc,

Fig. 4 is a view of the reverse side of the game counting disc, and,

Fig. 5 is an enlarged transverse section of the same, partly in elevation.

Referring now more particularly to the drawings wherein like reference characters indicate like parts, it will be seen that there is provided in a manner similar to the construction described in my application Serial Number 468,262, a base 10 having project-

ing therefrom a plurality of posts 11^a 11^b 11^c 11^d and 11^e. Obviously any number of these posts may be provided but in the illustrative example of counter described herein 5 and which, as hereinbefore stated, is particularly adapted for counting the game of bridge, five of such posts are shown. Disposed on each post is a plurality of chips 12, these chips being preferably six in number. It is desirable however, though not necessary, that the chips contained on each post be of a distinguishing color from each of the other sets of chips and furthermore that the post be of a corresponding color so 10 15 that there will be no difficulty in identifying the proper post upon which to place a chip. Furthermore, the chips are given values such as illustrated in Fig. 1, the chips being successively valued at 10, 30, 50, 250 20 and 1000, these arbitrary amounts being selected to conveniently pay the scores made in bridge.

Upon each post there is disposed in a vertical row a series of numbers 11^f starting at 25 the center with zero and graduating in both directions in amounts according to the valuation of the chips contained on that particular post, as for instance on post 11^a in Fig. 2, these numbers starting with zero and 30 increasing toward the top and toward the bottom of the post by tens. For the purpose of properly distinguishing the plus and minus value of the amounts disclosed, the amounts graduating downwardly from 35 zero are preferably printed in red while those graduating upwardly are printed in black. Therefore, if for instance, three additional chips were put on post 11^a such as indicated by dotted lines the number visible 40 at the top of the pile of chips would be 30, thereby indicating that additional chips to the value of 30 had been placed upon this post. In a like manner if three chips were removed from the post 11^a the amount visible 45 at the top of the pile of chips would be 30, but this amount would be indicated in red thus distinguishing the minus quantity from the plus quantity.

Each post has delineated thereon a column 50 of numbers arranged in a like manner, the valuations of which increase in amounts in accordance with the valuation of the chips contained on that particular post as will be immediately apparent. Therefore at 55 any time the valuation of additional chips contained on any rack as well as the valuation of chips removed from any rack will be apparent.

For tallying the points of each game 60 there is provided a disc 13 having visible on both sides thereof a dial arrangement 14, the values of which extend from zero to 30. On one side is displayed the words "No game for us" and on the other side the 65 words "One game for us." In order to pro-

vide a relatively movable central portion for each disc the disc is preferably constructed of a pair of outer members 15 recessed centrally thereof to accommodate a revoluble central member 16. Between the two outer members 15 is an inner member 17, the central opening of which is larger than the central opening in the members 15. The rotary member 16 is composed of two outer disc-like members 18 and 19 and a central 70 portion 20 of a greater diameter. The members 18, 19 and 20 are superposed in the concentric relation thereby providing an annular lip or flange which reposes between the inner edge of the disc-like members 15. 75 The members 15 and 17 are thereupon fastened together in any suitable manner whereby a disc is provided wherein the outer member and the central portion are relatively rotatable. For facilitating the 80 rotation of the inner disc 16, the center thereof is apertured as at 21 to facilitate the grasping of the disc by the fingers of the player. One side 22 of the central disc 16 is preferably left white while the other side 90 23 thereof is preferably of a distinguishing color such for instance as blue. The rotary central portion 16 has delineated thereon on each side an arrow 24 which cooperates with the dial 14 for indicating the 95 points of the game.

Obviously by making the central rotary disc 16 of distinguishing colors on opposite sides and having delineated on one side the words "No game for us" and on the other side the words "One game for us" it will always be apparent which game of the rubber the points indicated on the disc relate to. Therefore the status of each player as regards the game score is made readily apparent and the tallying of the points of the game is made simple.

The racks of my improved game counter are used the same as the racks illustrated and described in my copending application above identified. Each player is given a rack with preferably six chips on each post. In counting, all the points made both at game and honors are paid for to the number nearest 10. For instance, 35 is counted 110 as 40 and so on. After each hand is played the loser spreads out on the table the chips representing each score made by the other side, whether at points or at honors. When the winner has acknowledged that all the 115 scores are accurately paid for he picks up the chips and puts them on his rack.

In counting the points in the game the disc 13 is used. Each player at the beginning lays the disc with the white side 22 120 of the central portion 16 upwardly and there appears therefore the words "No game for us." As the points in the game are made the disc is grasped at its outer edge preferably by the left hand and the central por- 125 130

tion taken between the thumb and forefinger of the right hand and rotated until the arrow 24 indicates the number of points scored in the particular hand. When one game of the rubber has been won by one side the disc is turned over so that the side 23 of a distinguishing color of the central portion 16 of the disc is up and then appears the words "One game for us" therefore immediately indicating that the side having this particular disc has one game in the rubber.

Obviously this game counter may be used for other games and if necessary fractions 15 of amounts between the valuations of the chips may be kept by the disc counter, therefore broadening the use of this counter materially. While the structure described and 20 illustrated herein has been found to be practical in every detail, it is not intended that this invention be limited but reservation is made to make such changes in construction as may come within the purview of the accompanying claims.

Having thus described the invention, 25 what I claim is:

1. In a game counter a rack having a base and a plurality of posts projecting from said base, a plurality of centrally apertured chips disposed on each post, each of said 30 posts being provided with a column of numbers for indicating the value of the chips on each post in excess of or less than the original number, said chips being in sets of different values and each chip having its 35 value indicated thereon.

2. In a game counter, a rack including a plurality of posts, a plurality of apertured chips disposed on each post and adapted to be exchanged between the players, each post 40 being provided with a column of numbers consisting of two sets inversely arranged, with the zero common to both sets of numbers arranged at the center of the column for indicating the value of the chips in ex- 45 cess of or less than the original number.

DONALD McDONALD.
